UNITED STATES PATENT OFFICE.

REZEAU B. BROWN, OF MILWAUKEE, WISCONSIN, ASSIGNOR TO RITER-CONLEY MANUFACTURING COMPANY, OF PITTSBURGH, PENNSYLVANIA, A CORPORATION OF NEW JERSEY.

GAS-GENERATING APPARATUS.

1,168,055.

Specification of Letters Patent. Patented Jan. 11, 1916.

Application filed October 14, 1914. Serial No. 866,600.

To all whom it may concern:

Be it known that I, REZEAU B. BROWN, a citizen of the United States, residing at Milwaukee, in the county of Milwaukee and 5 State of Wisconsin, have invented certain new and useful Improvements in Gas-Generating Apparatus, of which the following is a specification.

This invention relates to improvements in 10 apparatus for generating gas, and more particularly to the means for closing the connection between the stand-pipe and a retort at the will of the operator.

The present invention relates more particularly to the type of structures disclosed in the patent to Barnum and Carpenter, Number 1,091,111, of March 24, 1914, in which a stand-pipe is shown as located between adjacent vertical rows of retorts, each 20 retort having a connection with the stand-pipe, the latter being in turn connected to a take-off common to a plurality of similar stand-pipes. In the structure of the said patent, the connections between the retorts 25 and the stand-pipe are permanently open, no means being shown for shutting off communication between any one of the retorts and its stand-pipe.

The present invention is designed to provide closure means for such connections, said means being of a simple character and readily under the control of the operator, enabling him to open or close communication at will, the closure means being located within 35 the stand-pipe and coöperating with the stand-pipe end of the connection, the object being to provide a structure and arrangement which will enable either one of a pair of retorts having their connections opposing each other in the stand-pipe to be closed at will or both remain open.

To these and other ends, the nature of which will be readily understood as the invention is hereinafter disclosed, said invention 45 consists in the improved construction and combination of parts hereinafter fully described, illustrated in the accompanying drawings, and more particularly pointed out in the appended claims.

In the accompanying drawing, in which similar reference characters indicate similar parts in each of the views, Figure 1 is a front

elevation, partly in section, of a portion of a gas generating apparatus, the views showing two vertical rows of retorts forming a 55 bench and a third vertical row forming a part of an adjacent bench, with a stand-pipe common to retorts of adjacent benches, and also a stand-pipe located at one end of a stack, and therefore coöperating with but 60 one vertical row; Fig. 2 is a vertical sectional view on the line 2—2 of Fig. 1; and Fig. 3 is a horizontal sectional view taken on the line 3—3 of Fig. 1.

In the drawings, 5 designates each of a 65 plurality of retorts having connections 6 with stand-pipes 7, the stand-pipe at the left of Fig. 1 being connected to the vertical rows of retorts on its opposite sides, the stand-pipe at the right being connected to a single 70 vertical row. As will be seen from Fig. 1, the connection 6 from retorts on the same horizontal plane directly oppose each other in the intervening stand-pipe. This fact enables me to provide a simple closure means 75 which is extremely effective and readily manipulated by the operator. The particular means employed by me for this purpose is a member 8 having curved faces on its opposite sides with a vertical diameter greater 80 than a cross sectional area of either connection with which it is adapted to coöperate. A preferred form of member is a sphere, as that form provides a sufficient weight and a suitable curvature for the purpose. 85

The member is connected to one end of an arm 9 which preferably extends in the form of a shaft 10 through a bearing or bushing 11 carried by the front of the stand-pipe, suitable packing being employed if desired, 90 to prevent leakage of gas therethrough. The outer end of the shaft is provided with a suitable latch mechanism of simple design, the latch being preferably operative with respect to the means when the member 8 is 95 mid-way between its extremes of movement, the position shown, for instance, in the stand-pipe at the right of Fig. 1, or in connection with the lower pair of retorts which lead to the stand-pipe at the left of Fig. 1. 100

As will be seen, the shaft 10 is located below the member 8, thus placing the support for the member 8 in such position that in moving from a point of balance (the mid-

way position of the member) toward their connection, the path of movement is in a direction which permits the weight of the member to aid in moving the member to its 5 seating position; in addition, this weight component is effective in retaining the member in its seated position.

As will be seen, the shaft arm and member 10 form practically a unitary structure movable in a manner to provide a swinging movement of the member 8 with the shaft 10 as the axis, the particular shape of the member 8 being such that it accommodates itself to its seat (the latter being of any preferred arrangement, as at 6^a) without the use of any 15 particular form of connection between the arm and member, the structure enabling the use of a rigid connection at this point. In addition, the member is so shaped as to 20 afford a minimum of resistance to the passage of the gas through the stand-pipe from retorts above or below, depending upon the direction of flow of gas through the stand-pipe, the curved surfaces providing no 25 pocket formation to act as a collecting agency for impurities which may be carried by the gas.

As seen in Fig. 1, the member can be 30 swung into engagement with either seat or be positioned at a point mid-way of its seats, the latter position placing the member in what may be considered as a balanced condition. Since the seats form stops which limit the extremes of movements of the 35 member 8, it will be readily understood that a simple latch mechanism may be employed, one type of which is shown in the drawings, it being necessary only to lock the member in its non-closing position. Obviously, a 40 removal of the holding device and an over-balancing of the member 8 will cause it to automatically seat itself. As will be seen in connection with the stand-pipe at the right in Fig. 1, the same arrangement of 45 parts may be employed with stand-pipes in which the retorts open thereinto on one side only. The shafts 10 are located substantially in a plane extending mid-way between opposing connections; consequently, the 50 movement of the member 8 from its intermediate position to its position in contact with its connection seat is sufficient to cause the weight of the member to become effective in holding the member to its seat without 55 the aid of additional holding mechanism. Valves 8 and their coöperating connections are of such size, weight and ruggedness that as the members move to position on seats 6^a, the impact or jarring effect tends to 60 break up deposits around the seat and on the member 8, and permitting the member to more closely fit its seat, both the member and its seat being thus kept practically clean during the operation of the apparatus.

65 What I claim is:

1. In gas generating apparatus, a stand-pipe, a retort communicating therewith through a lateral connection, and closure means therefor comprising a member carried rigidly by an arm, said arm having a lateral 70 extension extending through the front wall of the stand-pipe below the plane of the connection, whereby the member may have a swinging movement toward and from its seat and be held thereon by the weight of 75 the member, said member having a curved face opposing the communication passageway.

2. In gas generating apparatus, a vertically-extending stand-pipe, a pair of retorts 80 communicating therewith through connections opposing each other in the stand-pipe, and swinging means within the pipe adapted to close either connection at will, said means swinging on an axis located below the plane of the connections, said means including a member having curved faces 85 opposing the connections.

3. In gas generating apparatus, a vertically-extending stand-pipe, a pair of retorts 90 communicating therewith through connections opposing each other in the stand-pipe, and swinging means within the pipe adapted to close either connection at will, said means swinging on an axis located below the plane 95 of the connections, said means including a spherical member having a diameter greater than the cross-sectional area of either communication-passageway.

4. In gas generating apparatus, a vertically extending stand-pipe, a pair of retorts communicating therewith through connections opposing each other in the stand-pipe, and swinging means within the pipe adapted to close either connection at will, said means 105 swinging on an axis located below the plane of the connections, the connections having seats acting to limit the swinging movements of the means, said means having an external operating member, and means coöperating 110 with said member for retaining said closure means at an intermediate position to maintain communication between the stand-pipe and both retorts.

5. In gas generating apparatus, the combination of a plurality of retorts arranged one above the other, a mouth-piece for each retort forming an end extension thereof, a stand-pipe arranged vertically at one side of and closely adjacent to the mouth-pieces, 120 relatively short lateral conduits extending from the mouth-pieces and separately opening one above the other through a vertical wall of the stand-pipe and with a valve seat at the juncture of each conduit with the 125 stand-pipe, and a plurality of independently operating valves within the stand-pipe and mounted to oscillate about horizontal axes disposed transversely of the stand-pipe, each valve adapted to coöperate with one of said 130

valve seats for closing communication between the corresponding retort and the stand-pipe.

6. In gas generating apparatus, a vertically extending stand-pipe, a pair of retorts communicating therewith through connections opposing each other in the stand-pipe, and swinging means within the pipe adapted to close either connection at will, said means

including a member having curved faces 10 opposing the connections.

In testimony whereof I affix my signature in presence of two witnesses.

REZEAU B. BROWN.
